UNITED STATES PATENT OFFICE.

WILLIAM HENRY JOSEPH FITZGERALD, OF BRAINTREE, MASSACHUSETTS.

WRENCH.

1,004,562.

Specification of Letters Patent.

Patented Oct. 3, 1911.

Application filed June 12, 1911. Serial No. 632,557.

To all whom it may concern:

Be it known that I, WILLIAM HENRY JOSEPH FITZGERALD, citizen of the United States, residing at Braintree, in the county 5 of Norfolk and State of Massachusetts, have invented certain new and useful Improvements in Wrenches, of which the following is a specification.

My invention relates to wrenches, and the 10 invention consists in an improvement upon the wrench patented by John R. Long, of Akron, Ohio, June 9, 1908, and numbered 890,146, and further improved and patented by him April 26, 1910, No. 955,974.

15 In the accompanying drawings, Figure 1 is a side elevation of the wrench embodying my improvement. Fig. 2 is a cross section on line 2—2, Fig. 1, and Fig. 3 is a cross section on line 3—3. Fig. 4 is a side elevation 20 of the jaw member with the jaws closed and a sectional view of the connecting yoke. Fig. 5 is a perspective view of the spring employed with said parts.

At least two inherent defects have been 25 found in the wrench as developed under the foregoing patents which the present invention seeks to remedy, and these defects appear especially in the use or handling of the wrench. The first of these and possibly the more serious is the constant tendency of the sliding jaw or member *d* and the yoke or keeper *c* to wedge fast upon each other when the two jaws meet as seen in Fig. 4. This tendency has been so decided that 30 frequently the jaw *d* would become so firmly locked that it required much hammering and waste of time to get it released, but with the danger of a recurrence of the trouble the next moment. This was a most 35 serious objection to the wrench, even with persons skilled in its use while the novice was at a great disadvantage and was liable to cast the wrench aside as inoperative. Then, assuming that the parts were released, 40 the next trouble was that they were too loose and the sliding jaw and yoke were so free upon the main bar that they were not only liable to slide to wide open position but to lose mutual control. Of course it is to be 45 understood that the practical handling of this wrench has to be learned originally because it operates so differently from other wrenches, and that it is essentially a one-hand wrench with a thumb controlled member 50 through which the engaging position of

jaw *d* is always determined. Such control by the yoke was measurably satisfactory in the original wrench when it involved mere movement of the parts forward jointly to engaging position, but said yoke and jaw 60 were otherwise so entirely free to play back and forth in respect to each other that their freedom was a source of actual inconvenience and worked directly against what may be termed having the wrench in hand. In 65 other words experience with this wrench has demonstrated that it is desirable to have the jaw *d* and the yoke so united operatively that they can be manipulated together and will stay where they are put when 70 not engaged on an object and yet be free to be easily moved either way by means of the thumb. Such mutual working engagement and incident and kindred touch upon the handle-bar may be said to revolutionize 75 the operation of the wrench, and gives the user a complete and minute control as compared with the practical chaos and confusion under the old condition.

Now, referring specifically to the means 80 by which these improvements are worked out and advertiring first to the matter of wedging the jaws together as above described, it will be seen that the heel or back of the fixed jaw 2, or the main bar at that 85 point is provided with a shoulder or offset 3 approximately in line with the face of said jaw 2 but far enough out of line with said face to serve as a limiting stop or projection for the yoke at the end of its outward movement. This stop is arranged to 90 come where the yoke has not quite reached the locking position and hence it cannot tie or bind the member *d*. It follows that when the two jaws do come together face to face 95 as in Fig. 4 the yoke *c* is arrested by said stop and can go no farther. Of course there is no advantage in bringing the jaws face to face and hence the wedging of them together in that position is very objectionable 100 and an obvious defect in construction. By my improvement this is impossible. The second improvement above referred to as desirable comprises means for holding the jaw *d* and yoke *c* operatively together upon 105 the handle-bar *b*. These means in this instance are frictional and comprise a spring *s* located in a transverse channel 5 within the front edge of yoke *c* and having its body slightly curved so as to bring its ends out 110

into frictional contact with the flat edge surfaces 6 and 7 of the handle-bar *b* and jaw *d* respectively, while the middle of the spring lies in said channel. The said spring is flat 5 and its bearing surfaces at 6 and 7 are comparatively slight but yet they are sufficient to give the yoke movement control over jaw *d* in both directions, while at the same time both parts will stay where they 10 are released whatever the position of the wrench in the hand. This is very important because formerly if the wrench was held upright in one direction the said parts would gravitate to one end, and if reversed 15 in position they would gravitate to the other end regardless of where they were really wanted. In other words the parts were free individually and without mutual control. By my improvement the said parts are 20 brought under a unitary control and will rest where they are left whatever the position of the wrench. They will do this whether yoke *c* be tight or loose on part *d*. The same joint movement of parts *c* and *d* 25 occurs if the thumb engages the part *d*, as sometimes occurs. Incidentally under the action of said spring the said parts usually hold a close working position on bar *b* and this promotes locking of the jaws on an 30 object and, upon the whole, greatly simplifies the action of the wrench.

What I claim is:

1. A wrench comprising a handle member having a fixed jaw and a tapered main bar, 35 a loose jaw having a tapered shank adapted to slidably engage said main bar, a yoke enclosing said loose jaw and main bar, and a spring engaged with the main bar and the

loose jaw to hold the parts in any adjusted position.

2. A wrench having a main bar with a jaw at its end and tapered on its outer edge toward the said jaw, a slidable jaw mounted on said main bar having a substantially wedge shaped shank on its rear, a yoke enclosing said shank and bar and tapered to engage the outer edges of said parts and a spring inserted within one edge of said yoke and bearing at its ends upon said shank and said bar respectively.

3. In wrenches, a main-bar having a tapered shank with a jaw on its end, a slid- 45 able jaw mounted on said main-bar and having a tapered shank, a yoke confining said slidable jaw on said bar having a recess inside extending across both said main-bar and the shank of said slidable jaw and a spring located in said recess and bearing 50 against both said main-bar and said slid- able jaw.

4. A wrench consisting of a main-bar with a fixed jaw and a shank tapered toward said jaw, a slidable jaw with a reversely tapered shank mounted on said main-bar, a yoke operatively confined over said tapered shanks 55 and said main-bar having a projection on its outer edge adapted to serve as a stop for said yoke and prevent the same from binding on said parts when the said slidable jaw is forced forward to its limit.

In testimony whereof I affix my signature in presence of two witnesses.

WILLIAM HENRY JOSEPH FITZGERALD.
